TUBE HOLDER FOR SOLDERING AND THE LIKE

Heinrich H. Frank, Elyria, Ohio, assignor to The Ridge
Tool Company, Elyria, Ohio, a corporation of Ohio

Filed July 2, 1962, Ser. No. 70,774

Term of patent 14 years

(Cl. D54—1)

FIG. 1 is a plan view of a tube holder for soldering and the like; it being understood that the spring shown in full lines extends the full length of the broken line portion; and

FIG. 2 is a view in elevation, from the left side of FIG. 1.

The other side is substantially the same in appearance as the side illustrated except for the concave shape as shown in FIG. 2.

I claim:

The ornamental design for a tube holder for soldering and the like, as shown and described.
